(57) **CLAIM**

The ornamental design for a contoured massager with extension, as shown and described.

DESCRIPTION

FIG. 1 is a perspective view of a contoured massager with extension in accordance with the present invention;

FIG. 2 is a left view of the contoured massager with extension shown in FIG. 1;

FIG. 3 is a right view of the contoured massager with extension shown in FIG. 1;

FIG. 4 is top view of the contoured massager with extension shown in FIG. 1;

FIG. 5 is a bottom view of the contoured massager with extension shown in FIG. 1;

FIG. 6 is a back view of the contoured massager with extension shown in FIG. 1; and,

FIG. 7 is a front view of the contoured massager with extension shown in FIG. 1.

The broken lines shown in the drawings represent unclaimed portions of the design and form no part thereof.
